UNITED STATES PATENT OFFICE.

CHARLES F. SIMONIN AND ISAAC M. SIMONIN, OF PHILADELPHIA, PENNSYLVANIA.

PROCESS OF AND APPARATUS FOR TREATING GARBAGE.

SPECIFICATION forming part of Letters Patent No. 466,579, dated January 5, 1892.

Application filed May 13, 1891. Serial No. 392,569. (No model.)

To all whom it may concern:

Be it known that we, CHARLES F. SIMONIN and ISAAC M. SIMONIN, both citizens of the United States, and residents of Philadelphia, 5 Pennsylvania, have invented certain Improvements in Treating Garbage or Swill and in Apparatus for such Treatment, of which the following is a specification.

The object of our invention is to provide an 10 economical and commercially successful process and apparatus whereby garbage or swill can be treated by a chemical reagent for the purpose of recovering from it the constituents which have a marketable value, and this object we attain in the manner hereinafter set forth, reference being had to the accompanying drawing, which represents in diagrammatic form an apparatus constructed in accordance with our invention for carrying out 15 the process, which also forms part of said invention.

In treating garbage or swill for the recovery therefrom of those constituents which possess a market value the most rigid economy must 20 be observed; otherwise the value of the resultant product will be less than the expense of treatment. Hence not only must great precaution be taken to prevent loss or waste of the reagent, but the expenditure of fuel required in carrying out the process must also 25 be reduced to a minimum. The process and apparatus forming the subject of our invention have therefore been devised with these objects in view.

30 The reagent which we use is benzine, naphtha, or other volatile hydrocarbon which is of less specific gravity than water and which has the effect of a solvent upon grease or fats submitted to its action, especially when such 35 action is under heat.

Water constitutes by far the greatest percentage of the garbage or swill which is to be treated, and any attempt to remove this water by drying the garbage before treatment would, 40 because of its expense, be fatal to the commercial success of the process. A chemical reagent of the character specified, however, not only has the effect of dissolving the grease or fat which may be present in the garbage, but 45 it also has the effect of displacing the water therein, so that it may be said to have the ef-

fect of drying the garbage in so far as that means the expulsion of the water therefrom, so that the latter will not affect the action of the reagent upon the grease or fat. The water 55 being thus dislodged can be conveniently separated from the reagent and the grease in solution therein, so that the subsequent distillation, for the purpose of driving off the reagent from the grease in order that it may be 60 again used in the treatment, is not hampered and rendered expensive by the presence of the water and the necessity of vaporizing the latter, as well as the reagent, in the still.

The accompanying drawing illustrates one 65 form of apparatus which we have employed, and we will give a description of the construction and operation of the same in order that our invention may be clearly understood.

A is a vessel which may be termed a "storage-tank," in which the garbage or swill is first deposited, the lower end of this vessel communicating through a valved pipe *a* with the extractor B, and the upper portion of the vessel being, if desired, provided with a pipe *a'*, 70 75 communicating with a fan *a*² for drawing off any gases or vapors which may be evolved from the mass while contained in said storage-tank.

A vessel, which we term a "settler," is represented at D, and F represents a still, G a heater for the fluid reagent, H a condenser, J J a pair of reagent-holders, and I a separator interposed between said reagent-holders and the condenser. 80 85

The upper portion of the extractor is in communication with the condenser through a pipe *b*, having a valve *b'*, and the upper portion of the still is also in communication with the condenser through a pipe *f*, having a valve *f'*, 90 and the pipes *b* and *f* are connected by a cross-pipe N to a branch pipe P, a valve *n'* being interposed in the cross-pipe between the pipe P and the pipe *b* and a valve *n*² being interposed between the pipe P and the pipe *f*. 95 The branch pipe P communicates through a pipe *a*³ with a heating-coil *a*⁴ in the storage-tank, this coil having a return-pipe *a*⁵ leading to the condenser and provided with a valve *a*⁶, while the communication between the pipe P and the pipe *a*³ is governed by a valve *a*⁷. The pipe P also communicates through a pipe 100

b², having a valve b³, with a heating-coil b⁴ in the lower portion of the extractor B, and this coil communicates with the condenser through a pipe b⁵, having a valve b⁶. Communication 5 between the pipe P and the heater G is effected by a pipe g, having a valve g', and the lower portion of the heater is in communication with the condenser through a pipe g², having a valve g³. The lower portion of the condenser 10 H communicates through pipes h' h² with the separator I, which has a drain-pipe i, with valve i', said separator being also in communication with the reagent-holders J through a pipe i² and its branches. Each of the reagent-holders is in communication through a pipe j, having a valve j', with the inlet of a pump K, which discharges into a pipe k, the latter passing through the heater G and being formed 15 therein into a series of coils or convolutions k' or being otherwise so disposed as to cause extended travel of the reagent within the heater. The pipe k communicates with the bottom of the extractor, and it is also in communication with the upper portion of the settler D through a pipe d, having a valve d', and in the pipe k, between the pipe d and the heater G, is interposed a valve k². The pipe k has a branch s, with valve s', through which, when desired, the extractor B may be 20 discharged of its liquid contents or a portion of the same, and the settler D has at the bottom a discharge-pipe d², with valve d³, and a pipe d⁴, with valve d⁵, through which it communicates with the upper portion of the still, 25 while communication between the top of the settler and the condenser is established by means of a pipe d⁶ having a valve d⁷. The still contains a steam-coil S and has at the bottom a discharge-pipe f², with valve f³. The 30 pipe P communicates through a pipe m, having a valve m', with an ejector or jet-pump M, having an inlet-pipe m², which communicates with the reagent-holders J, and is provided with a valve m³, the outlet-pipe m⁴ of said 35 pump M communicating with the pipe k at a point between the extractor and the branch pipe d, and said pipe m⁴ being provided with a valve m⁵.

The storage-tank A should be provided with 40 a suitable opening for the admission of the garbage, and the extractor B should be provided with an opening for the removal of the solid product resulting from the treatment, such opening of course being closed during 45 the treatment.

When the apparatus is in full working condition, both the extractor and the still are in 50 operation, and the vapor from these vessels escapes therefrom through the pipes b and f, and by manipulating the valves b' and f' and n' and n² as much or as little of this vapor as 55 desired may be permitted to pass directly into the condenser, the remaining volume passing into the pipe P; or the valves b' and f' may be closed and the entire volume of vapor from the extractor and still may be directed into said pipe P, from which it passes

through the pipe g into the heater G and through the pipe b² into the heating-coil b⁴ in the lower portion of the extractor, a portion 70 of the vapor being also in some cases directed to the heating-coil a⁴ in the storage-tank—as, for instance, in the winter season, when the garbage or swill is received in a frozen condition, it being then desirable to thaw the mass 75 in the storage-tank before admitting it to the extractor.

The pump K draws the liquid reagent from the holders J and forces it through the heater and pipe k into the extractor until the material therein is completely immersed in said heated liquid reagent, whereupon the pump is stopped and the valve k² closed, the heating-coil a⁴ then maintaining the liquid reagent 80 in the extractor in the proper heated condition. During the extracting operation the valves d', m', m³, m⁵, and s' are also closed; but when the treatment has been continued for the proper length of time the valve s' may be 85 opened to permit the discharge from the extractor of the water which has been dislodged by the reagent and has accumulated in the lower portion of the extractor, after which said valve s' is closed and the valve d' opened, so that the reagent, with the grease in solution 90 therein, will be driven into the settler D by reason of the pressure in the extractor; or, if desired, the water may also be driven from the extractor into the settler D, together with the reagent and grease, and separated from the latter in the settler by drawing it off through the drain-pipe d², the reagent, with the grease 95 in solution therein, being drawn into the still as required, and the grease being removed from the still through the drain-pipe f² after 100 the volatile reagent has been driven off from said grease by the heat from the steam-coil S.

In order to retreat the charge in the extractor or to treat a fresh charge therein, the valve d' is closed, the valve k² again opened, 110 and the pump K started, so as to again force the liquid reagent through the heater G and into the extractor, the pump being stopped when the desired amount of reagent has been introduced and the valve k² being then closed 115 and the reagent maintained in the heated condition in the extractor by means of the heating-coil b⁴. Any vapors which enter the vessel H are therein condensed and the liquid 120 flows into the separator I, in the lower portion of which the water of condensation accumulates and can be drawn off from time to time through the valved pipe i, the liquid solvent passing through the pipe i² into the holders J.

In some cases the jet-pump M may be used in addition to or in place of the pump K as a means of forcing the liquid reagent into the extractor and at the same time heating the same, the valves m', m³, and m⁵ in this case 130 being opened, so that the jet of heated vapor from the pipe m will induce a flow of the liquid reagent through the pipe m² and out through the pipe m⁴, the heated vapor being

thus brought into intimate contact with the liquid reagent, so as to be condensed or partially condensed thereby at the same time that the liquid is heated by it. This effect of condensation or partial condensation of the heated vapor likewise results from passing the same through the heating-coils in the storage-tank and extractor and through the heater G.

10 It will be noted that our improved apparatus not only provides for the complete saving of all of the liquid reagent used in the treatment, so as to permit of its use again and again without waste, but said apparatus also 15 involves the use of steam only for the purpose of heating the coil in the still and for operating the pump K when the jet-pump M is not used, and in some cases, also, for heating the reagent in the extractor when the operation 20 is first started. Hence the expenditure of fuel in carrying out the process is reduced to a minimum.

Although it is preferable to use both the heater G and the heating-coil in the extractor, either of these may be used to the exclusion of the other, and although it is also preferable to use one or more reagent-holders J the heater G itself may in some cases constitute, also, the reagent-holder. For instance, in the 30 construction shown the coils in the vessel G would constitute such reagent-holder and would receive the reagent directly from the condenser if the latter were used, for in cases where the passage of the vapor through the 35 heating-coils in the storage-tank and extractor and through the heater and connecting-pipes is sufficient to effect the condensation of said vapor a special condensing-vessel may be dispensed with.

40 Another obvious modification of our invention is one in which the pipes are so arranged that the vapor-pipe from the still supplies the heating-coil in the extractor, and the vapor-pipe from the latter supplies the heater G and the coil in the storage-tank.

The settler D provides for the deposit of foreign matters of a solid character which may be carried over into the settler from the extractor, so that these foreign matters can 50 be withdrawn from the settler and prevented from passing into the still, where their presence would be objectionable.

Having thus described our invention, we wish it to be understood that we do not desire 55 to claim, broadly, the extraction of fats or fatty matters by means of benzine, naphtha, or other volatile reagent of low specific gravity, as this has long been known and practiced; but

60 We claim as our invention and desire to secure by Letters Patent—

1. The within-described method of treating swill or garbage containing water, said method consisting in immersing the garbage while 65 in a suitable vessel in a heated liquid reagent which is a solvent of grease and is of less specific gravity than water, so as to displace

the water in the garbage and take up the grease, separating the water from the reagent with the grease in solution therein, distilling 70 the reagent from the grease, and subjecting the fresh supplies of liquid reagent to the action of the vaporized reagent given off in the treatment, whereby the liquid reagent is heated and the vaporized reagent is at the same 75 time condensed or partially condensed, substantially as specified.

2. The combination, in apparatus for treating garbage with a heated liquid reagent, of the following elements, namely: an extractor, 80 means for conducting liquid reagent thereto, a still, a communication through which liquid can be conveyed from the extractor to the still, means for separating the water from the reagent and grease before the latter enters the 85 still, a heater for the liquid reagent, vapor-pipes leading from the extractor and still, and a vapor-conducting pipe leading to the heater, substantially as specified.

3. The combination, in apparatus for treating garbage with a heated liquid reagent, of the following elements, namely: an extractor, 90 a still, a settler interposed between the extractor and still, means for conducting liquid reagent to the extractor, a heater for the liquid reagent, vapor-pipes leading from the extractor and still, and a vapor-conducting pipe 95 leading to the heater, substantially as specified.

4. The combination, in apparatus for treating garbage with a heated liquid reagent, of the following elements, namely: an extractor, 100 a still, a settler interposed between the extractor and still, means for conducting liquid reagent to the extractor, a heater independent of the extractor and adapted to heat the liquid reagent before the latter enters the extractor, vapor-pipes leading from the extractor and still, and a vapor-conducting pipe 105 leading to the heater, substantially as specified.

5. The combination, in apparatus for treating garbage with a heated liquid reagent, of the following elements, namely: an extractor, 110 a still, a settler interposed between the extractor and still, means for conducting liquid reagent to the extractor, a heater for the liquid reagent contained within the extractor, a second heater for said reagent independent of the extractor, vapor-pipes leading from the 115 extractor and still, and pipes for conveying vapor to both of said heaters, substantially as specified.

6. The combination, in apparatus for treating garbage with a heated liquid reagent, of 120 the following elements, namely: an extractor, a still, a settler interposed between the extractor and still, means for conducting liquid reagent to the extractor, a condenser, a heater for the liquid reagent, vapor-pipes leading 125 from the extractor and still, and pipes for conveying vapor first to the heater and then to the condenser, substantially as specified.

7. The combination, in apparatus for treat-

- ing garbage with a heated liquid reagent, of the following elements, namely: an extractor, a still, a settler interposed between the extractor and still, means for conducting liquid reagent to the extractor, a condenser, a heater for the liquid reagent, vapor-pipes leading from the extractor and still to the condenser, and pipes for conveying vapor first to the heater and then to the condenser, substantially as specified.
8. The combination, in apparatus for treating garbage with a heated liquid reagent, of the following elements, namely: a storage-tank having a heater therein, an extractor 15 communicating with said storage-tank, a still, a settler interposed between the extractor and still, means for conducting liquid reagent to the extractor, a condenser, vapor-pipes leading from the extractor and still to the condenser, and a pipe for conveying vapor from
- 5
- 10
- 15
- 20

said pipes to the heater in the storage-tank, substantially as specified.

9. The combination, in apparatus for treating garbage with a heated liquid reagent, of the following elements, namely: an extractor, a still, a settler interposed between the extractor and still, means for conducting liquid reagent to the extractor, a holder for the liquid reagent, vapor-pipes leading from the extractor and still, a jet-pump communicating 25 with the reagent-holder and with the extractor, and a pipe for conveying the vapor to said jet-pump for the purpose of operating the same, substantially as specified.
